UNITED STATES PATENT OFFICE.

WALTER J. DREW, OF GRAND RAPIDS, MICHIGAN, ASSIGNOR TO THE
BISSELL CARPET SWEEPER COMPANY, OF SAME PLACE.

CARPET-SWEEPER.

SPECIFICATION forming part of Letters Patent No. 443,163, dated December 23, 1890.

Application filed June 7, 1890. Serial No. 354,596. (No model.)

To all whom it may concern:

Be it known that I, WALTER J. DREW, a citizen of the United States, residing at Grand Rapids, in the county of Kent and State of Michigan, have invented new and useful Improvements in Carpet-Sweepers, of which the following is a specification.

This invention relates to that type of carpet-sweeper wherein two supporting-wheels are arranged at each end of the sweeper-case to co-operate with a brush-shaft extending continuously from end to end of the case.

The objects of the present invention are to provide novel means whereby a sweeper having a continuous brush-shaft can be turned at varying angles on the floor without the pulleys slipping on the supporting drive-wheel at either end of the case, thereby relieving the rubber tires from undue wear when turning the sweeper, and finally to provide a novel brush-shaft driven at one end of the sweeper, but capable of being reversed and driven at the opposite end of the sweeper as one pair of the rubber tires becomes unduly worn.

To accomplish all these objects my invention involves the features of construction, the combination or arrangement of parts, and the principles of operation hereinafter described and claimed, reference being made to the accompanying drawings, in which—

Figure 1 is a top plan view of a four-wheel sweeper embodying my invention. Fig. 2 is a longitudinal sectional view taken on the axis of the brush-shaft. Fig. 3 is an end elevation of the same; and Fig. 4 is a detail perspective view of the brush-shaft, to show its fast and loose pulleys.

In order to enable those skilled in the art to make and use my invention, I will now describe the same in detail, referring to the drawings, wherein—

The numeral 1 indicates a carpet-sweeper case, 2 its end walls, 3 the dust-pans, and 4 the bail, all of which may be of any construction suitable for the conditions required, the case being supported, as usual, by a pair of supporting-wheels 5, at each end provided with rubber tires 6 for driving the brush-shaft by friction. The brush-shaft may be supported

in any suitable manner; but if a self-adjusting brush is desired I prefer to employ an elastic band 7 at each end of the casing, having bent ends 8, and provided centrally between such ends with a vertical slot 9, in which slots work the journals 12 of the brush-shaft 10.

In a four-wheeled sweeper having a brush-shaft provided with a pulley at each end, which is so attached as to revolve in unison with the shaft, if the sweeper be turned at different angles while traversing the floor one of the pulleys slips on the rubber tires of the supporting-wheels at that end of the sweeper, and consequently the tires become unduly worn and inefficient. To avoid this objection I provide the brush-shaft with a rigidly-attached or fast pulley 13 at one end and with an idle or loose pulley 14 at the opposite end. The idle or loose pulley is preferably mounted on a cylindrical hub end 15 of the brush-shaft, and the construction is such that while the pulley 13 serves to drive the brush-shaft and revolves therewith, the pulley 14 at the opposite end could stand stationary while the brush-shaft revolves therein. In consequence of this combination, when the sweeper is turned at angles while traversing the floor the idle or loose pulley will not slip on the rubber tires of the supporting-wheels at that end, thereby saving the tires from undue wear, for the idle or loose pulley can be freely revolved by a pair of the supporting-wheels without revolving the brush, or the brush can be revolved by the other pair of wheels without revolving the idle or loose pulley.

The construction is such that when the tires on those wheels which drive the fast pulley become worn or injured the brush can be quickly removed and reversed end for end and replaced, when the fast pulley will be driven by the perfect tires on the opposite set of supporting-wheels.

The idle or loose pulley co-operates with a pair of the wheels at one end of the sweeper, in that the brush-shaft is thereby properly centered and supported for effective work.

What I claim is—

1. The combination, with the case of a four-wheeled carpet-sweeper, of a brush-shaft hav-

ing an idle or loose pulley at one end and a fast pulley at the opposite end, substantially as described.

2. The combination, with the case of a four-wheeled carpet-sweeper, of a reversible brush-shaft having an idle or loose pulley at one end and a fast pulley at the opposite end, substantially as described.

In testimony whereof I have affixed my signature in presence of two witnesses.

WALTER J. DREW.
